ENVELOPE OR BAG MAKING MACHINERY

Abraham Novick, Flushing, N. Y., assignor to
 F. L. Smith Machine Co., Inc., New York,
 N. Y., a corporation of New York

Application December 12, 1933, Serial No. 701,948

7 Claims. (Cl. 271—76)

This invention relates to envelope or bag making machinery and has for an object to provide improved means for applying gum for the end fold, for ironing down the end fold, and for conducting the bags away from the operating instrumentalities and for delivering them in definite and orderly relation.

Other objects and advantages will hereinafter appear.

10 In the drawings forming part of this specification,

Figure 1 is a fragmentary, sectional, side elevation illustrating mechanism embodying features of the invention:

15 Figure 2 is a fragmentary, detail, diagrammatic view illustrating the delivery of a blank from one conveyor to another;

Figure 3 is a fragmentary plan view illustrating the mechanism of Figures 1 and 2;

20 Figure 4 is a fragmentary sectional elevation illustrating the forming of a tuck in the bag;

Figure 5 is a view similar to Figure 4 illustrating the same parts a little farther advanced in their cycle;

25 Figure 6 is a fragmentary sectional elevation illustrating the ironing of the end fold and the first stage of the delivery of a blank to a longitudinal conveyor; and

Figure 7 is a view generally similar to Figure 6 showing the blank after the longitudinal conveyor has taken control of the same.

The machine comprises a mechanism (not shown) for forming a continuous web of paper, "Cellophane" or other suitable bag material into a tube, and for severing the tube into bag blanks of suitable lengths. The blanks are delivered by feed roll couples 1, 2 and 3, 4 to a tucking, pasting and folding mechanism indicated generally by reference numeral 5. The mechanism 5 comprises two feeding cylinders 6 and 7 which run at the same speed and which cooperate to feed the blanks. The cylinder 6 has fixed upon it a bar 8 which pivotally and yieldingly supports a tucking bar 9. The cylinder 6 also includes two adjustable segments 10 which may be fixed in various adjusted relations to the main portion of the cylinder by means of bolts 11 and slots 12. A bar 13 is mounted in a radial slot 14 formed in the segment 10 and is movable toward and from the center of the cylinder. A gummer bar 15 is mounted upon the bar 13. An actuating arm 16 is secured to a shaft 16^a mounted upon the segments 10, said shaft having two forked arms 16^b, one at each end, and each arm embracing a pin 17 for oscillating the bar 13 toward and from

the axis of the cylinder 6. The actuating arm 16 carries a cam follower 18 which travels upon a stationary cam 19 the follower 18 being urged towards said cam by a spring 19^a. Oscillatory movement is imparted to the bar 13 for the purpose of projecting the gumming bar 15 beyond the periphery of the cylinder 6 at an appropriate point in the cycle to receive gum from a gum roller 20, which roller stands clear of the surface of the cylinder so as not to apply the gum thereto, and for retracting the gumming bar to a position substantially flush with the feeding surface of the cylinder 6 for engagement with the blank upon the periphery of the cylinder 7.

The cylinders 6 and 7 are so related that the 15 tucking bar 9 acts to tuck a leading end portion of the blank between fixed and movable jaws 21 and 22. The jaw 21 is a fixed part of the cylinder 7 while the jaw 22 is carried upon a rock shaft 23, which shaft also carries a cam follower 20 24. The shaft 23 is mounted in a block 25 which is removably held by bolts 26 in a radial slot formed in the cylinder 7. The cam follower 24 travels upon a stationary cam 27 and is effective when it rides onto a high part of the cam to 25 move the jaw 22 away from the jaw 21 to an open position. A spring 28 tends to restore the jaw 22 to closed position and is effective to do so as soon as the leading end of the bag blank 30 has been tucked between the jaws. The sequence 30 of operations is well illustrated in Figures 4 and 5.

When the blank has been tucked and gripped between the jaws 21 and 22 it is carried forward by the cylinder 7, and the gumming bar 15 is caused to apply gum to a portion of the blank 35 body 29 which is to be covered by the projecting blank flap 30. In the continued forward movement of the cylinder 7 the flap 30 is carried against a stationary folding plate 31 to fold said flap against the body. The flap then passes 40 beneath said plate 31 and is pressed lightly against the gummed face of the blank body. After this has been accomplished, it is desirable to iron down the folded over flap and to convey the blanks bodily away from the cylinder 7 45 in order that they may be delivered in an orderly relation to one another. In accordance with an important feature of this invention, provision is made of a conveyor mechanism 32 which serves both to cooperate with the cylinder 7 in ironing 50 down the folded flap and to conduct the blanks away from the cylinder 7 and deliver them in a predetermined relation to one another. The conveyor mechanism 32 comprises a pair of chains 33 which run upon sprockets 34 and 35 and which 55

are connected with one another by rigid bars 36. The bars 36 present outer faces which are generally in the form of cylinder segments and which are adapted to cooperate with the cylinder 7 in ironing down the folded bag end. Each bar also has pivotally mounted upon it gripper jaws 37. The gripper jaws 37 associated with each bar 36 are secured to a common rock shaft 37^a and are controlled by cams 38 and 39, engaged by arms 37^b secured to the rock shaft the cams 38 being secured to end plates 38^a of an auxiliary frame, and being effective to cause the gripper jaws to approach the cylinder 7 in an open condition and a return spring 37^c being effective to swing back the gripper jaws onto the leading end of the bag blank after such leading end has been fed between the gripper jaws 37 and the bar 36. The cam 38 is so shaped that the jaws 37 are not permitted to snap sharply against the bag material. This is a desirable construction since it prevents injury to materials such as "Cellophane" that might be damaged by a blow. The cross bars 36 occur along the conveyor at intervals equal in extent to the circumference of the cylinder 7, and the conveyor is driven at a linear speed equal to the peripheral speed of the cylinder 7.

The cam 27 acts to operate the gripper jaw 22 to an open position as the leading end of the bag blank nears the point at which it is transferred to the bar 36 and the gripper jaws 37. Stripper fingers 40 run in grooves 41 of the cylinder 7 and serve to intercept the leading end of the bag blank and to deflect it away from the periphery of the cylinder 7. The deflecting fingers 40 are so mounted upon a shaft 42^a supported by arms 42 carried by a rockable shaft 43. The arms 42 are normally held in position shown in Figure 1 by means of a spring and stop (not shown), but may be swung downward to afford access to the other parts when desired.

The shaft 44, upon which the sprockets 34 are mounted, also has fast upon it a series of notched disks 45 which coat with the cylinder 7 in guiding and feeding the blank. The notches 45^a of the disks 45 are so located and timed that they provide grooves for the bars 36 when the bars travel around the axis of the sprockets 34.

As viewed in Figure 1 the cylinder 7 rotates in a clockwise direction and the sprockets 34 in a counterclockwise direction. The blanks are accordingly carried away from the cylinder 7 in the lower stretch of the conveyor 32. A series of rods 46 forms a table for supporting the depending trailing ends of the blanks. The blanks are carried forward over guides 47 and above a transverse conveyor 48. The blanks are released and permitted to drop down away from the conveyor 32 when the gripper jaws 37 are moved to open positions by the cam 39. Stripper fingers 49 assist in separating the leading end of the blank from the cross bar, the cross bar being grooved to accommodate said fingers. The transverse conveyor 48 runs upon pulleys 50 and 51, the former of which is fast upon a shaft 52. The shaft 52 has fast upon it a worm wheel 53 which is driven by a worm 54. A link 55 is eccentrically mounted upon the worm shaft 56 at one end thereof, and acts to oscillate a bellcrank lever 57. The bellcrank lever in turn acts intermittently to rock a crank 58 fast upon a shaft 59. The shaft 59 has fast upon it a pair of cranks 60. The upper end of each of the cranks 60 has pivotally connected with it a pusher 61 which extends longitudinally of the conveyor 48 and rests by gravity upon the conveyor. As each bag is de-

posited upon the conveyor 48, it is moved forward a step by the pusher 61 and is thereafter carried by the conveyor at a uniform slow speed to a point at which the bags are removed from the conveyor by an operator.

The shaft 44 is supported in the main frame 62 of the machine, and hence controls the position of the left hand end of the conveyor mechanism 32. The shaft 63 at the opposite end of the conveyor mechanism 32 is stationary and forms part of the auxiliary frame including the side plates 38^a which are secured to each other by said shaft 63 and a bar 64, said frame being vertically adjustable. A link 65 is pivotally connected to the auxiliary frame 64 and extends downward through a stationary ear 66 which is provided on the main frame. Adjustable nuts 67 and 68 are provided above and below the ear 66 for setting the conveyor mechanism 32 at any desired elevation.

I have described what I believe to be the best embodiments of my invention. I do not wish, however, to be confined to the embodiments shown, but what I desire to cover by Letters Patent is set forth in the appended claims.

I claim:

1. In a bag machine, in combination, a feeding cylinder, a gripper carried thereby, a conveyor running in juxtaposition with the periphery of the feeding cylinder, said conveyor including a crossbar cooperative with the face of the cylinder to grip and positively advance a blank, a gripper carried by the conveyor, and means for transferring the leading end of a bag blanks from the cylinder gripper to the conveyor gripper while the blank is gripped between the conveyor cross bar and the cylinder surface.

2. In a bag machine, in combination, a feeding cylinder, a gripper carried thereby, a conveyor running in juxtaposition with the periphery of the feeding cylinder, said conveyor including a cross bar cooperative with the face of the cylinder to grip and positively advance a blank, a gripper carried by the conveyor, means for opening the cylinder gripper at a predetermined point to release the bag, means for intercepting the released leading end of the bag and deflecting it away from the cylinder, and means for causing the conveyor gripper to extend across the path of the deflected bag and then to swing back onto the same while the blank is gripped between the conveyor crossbar and the cylinder surface.

3. In a bag machine, in combination, a feeding cylinder, a gripper carried thereby, means for conducting the bag blanks away from the cylinder comprising a conveyor, grippers carried by the conveyor and means for transferring the leading end of a blank from the gripper on the cylinder to a conveyor gripper, the conveyor gripper being operated to carry a bag blank away from the cylinder at the lower side of the conveyor, a second conveyor running transversely beneath the first, and means for releasing the conveyor grippers at a predetermined point to cause the blanks to be dropped upon said transverse conveyor.

4. In a bag making machine, in combination, a feeding cylinder, a gripper carried thereby for gripping the leading end of a blank, a conveyor running in a circular path in juxtaposition with the periphery of the cylinder and in a straight path away from the cylinder, a segmental cross bar carried by the conveyor and traveling tangent to the cylinder in the circular part of its path for gripping a blank to the cylinder to co-

operate with the cylinder in positively feeding the blank, a gripper carried by the conveyor, and means for transferring the leading end of the blank from the cylinder gripper to the conveyor gripper while the blank is gripped between the cylinder and the cross bar.

5. A structure as set forth in claim 4 wherein the transferring means comprises means for causing the conveyor gripper to close gently upon the blank.

10. A structure as set forth in claim 4 wherein provision is made of means for opening the conveyor gripper to drop the blank at a point remote

from the cylinder, and wherein a slow moving transverse conveyor is provided to receive the dropped blank.

7. A structure as set forth in claim 4 wherein provision is made of means for opening the conveyor gripper to drop the blank at a point remote 5 from the cylinder, and wherein a slow moving transverse conveyor is provided to receive the dropped blank, and further characterized by means to move each bag forward a step as it is 10 deposited upon said conveyor.

ABRAHAM NOVICK.
